(57) **CLAIM**

I claim the ornamental design for a tool for a cleaning appliance, as shown and described.

DESCRIPTION

FIG. 1 is an underneath, front and side perspective view of a tool for a cleaning appliance of the design according to this invention.

FIG. 2 is a top view of a tool for a cleaning appliance of the design according to this invention.

FIG. 3 is an underneath view of a tool for a cleaning appliance of the design according to this invention.

FIG. 4 is a front view of a tool for a cleaning appliance of the design according to this invention; and,

FIG. 5 is a rear end view of a tool for a cleaning appliance of the design according to this invention.

The undisclosed portion of the sides which is not shown in the drawings forms no part of the claimed design.
